UNITED STATES PATENT OFFICE.

OLIVER W. GATCHELL, OF GREENSBORO, NORTH CAROLINA.

BRICK-PAVER'S BRIDGE.

Application filed June 27, 1922. Serial No. 571,202.

To all whom it may concern:

Be it known that I, OLIVER W. GATCHELL, a citizen of the United States, residing at Greensboro, in the county of Guilford and State of North Carolina, have invented a new and useful Brick-Paver's Bridge, of which the following is a specification.

This invention relates to bridges or supports especially designed for use in laying bricks or the like, the primary object of the invention being to provide a support to overlie the unpaved road surface, thereby supplying a foot rest for the person laying bricks to enable the workman to straddle his work, resting one foot on the bridge, while his other foot rests on the portion of brick already laid.

Another object of the invention is to provide a support or bridge of this character which may be easily moved over the road bed.

A still further object of the invention is to provide an adjustable bridge so that the same may be employed in connection with road beds of various widths.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is an elevational view disclosing a portable bridge or support as positioned on the curbs of a roadway.

Figure 2 is an enlarged fragmental elevational view disclosing one end of the bridge.

Figure 3 is a plan view disclosing one end of the bridge.

Figure 4 is an elevational view disclosing a modified form of the invention.

Figure 5 is a plan view disclosing one end of the bridge.

Figure 6 is a sectional view taken on line 6-6 of Figure 1.

Figure 7 is a plan view disclosing one end of the extension and manner of connecting the same, with one of the bridge heads.

Referring to the drawings in detail, the device includes a body portion 5 formed of

any suitable material, it being preferred however to construct the body portion of angle bar material, the same being curved upwardly bringing the surface of the bridge on an equal plane with the road surface 60 which has been laid.

One end of the body portion is cut away as at 6 to provide a clearance for the rollers 7, a portion of the bottom member of the angle bar extending beyond one end of the body 5 65 as at 8. The extreme end of the member 8 extends upwardly as at 9 where the same is formed with suitable openings to accommodate the pintles 10 of the rollers 7, while a portion of the vertical member of the body 70 portion or angle bar 5 extends inwardly where the same is formed with openings to accommodate the pintles of the rollers 7.

The opposite end of the body portion 5 is supplied with an adjustable section 12 which 75 is also formed of an angle bar cut away to accommodate the rollers 13, which rollers have pintles 14 and 15 respectively. The pintles 14 extend through suitable openings in the inwardly extended portion 16 of the 80 extension, while the pintles 15 extend through openings in the upwardly extended portion 17 formed integral with the extension. This angle bar 12 is formed with a plurality of spaced elongated openings 18, which openings accommodate the bolts 19 that are carried by the body portion 5, suitable nuts 20 being positioned on the bolts 19 to secure the body portion 5 and extension together.

Bolts 21 extend through the contacting members of the angle bars as clearly shown by Figure 2 of the drawings, whereby the body portion and extension are further held against displacement. From the foregoing it will be seen that by adjusting the member 12 with respect to the body, rollers which support the bridge may be adjusted with respect to each other adapting the bridge for use with roadways wherein the curbs are supported at various distances apart.

In the form of the invention as shown by Figure 4 of the drawings, the body portion of the bridge is indicated at 22 and is shown as curved upwardly bringing the surface of the bridge in a plane equal to the plane of the road surface which has been laid. Heads 23 are supported at the ends of the body portion 22, which heads are formed with suitable bearings to accommo-

date the rollers 24 that rest on the curbings 25.

These heads 23 are also formed with suitable openings to accommodate the truss rods 26 that are arranged on opposite sides of the body portion 22, the rods supporting the bars 27 that lie under the body portion 22 to reinforce the arms and prevent sagging of the bridge.

10 Forming a part of the bridge structure is an extension 28 which embodies opposed sections 29 secured together as by means of the securing bars 30, the width of the extension 28 being less than the width of the 15 head 23 associated therewith, to enable the extension to be positioned between the members 31 of the head, where the same may be bolted thereto as by means of the bolts 32.

This extension 28 permits of adjustment 20 of the bridge to lengthen or shorten the same as required, it being obvious that the distance between the curbs of a road is wider at curves.

From the foregoing it will be seen that 25 I have provided a portable bridge which may be used in road construction, the bridge being of such a construction as to permit a person laying bricks to straddle his work, thereby eliminating the necessity of a person turning his body to pick up the bricks 30 to be laid.

Having thus described the invention, what is claimed as new is:—

1. In a device of the character described, a body portion including an angle bar, an 35

extension in the form of an angle bar positioned under the body portion and adjustably secured thereto, and rollers at the end of the body portion.

2. In a device of the character described, 40 a body portion, heads supported at the ends

of the body portion, an extension secured to one of the heads, means under the body portion to support the weight of the body portion, and rollers carried by the heads.

3. In a device of the character described, 45 a body portion including an angle bar, an angle bar extension positioned under the body portion and having a plurality of elongated openings, bolts carried by the body portion and disposed within the openings to adjust the extension with respect to the body portion, nuts for holding the extension in its positions of adjustment, and rollers mounted at the ends of the body portion.

50 In testimony that I claim the foregoing as my own, I have hereto affixed my signature in the presence of two witnesses.

OLIVER W. GATCHELL.
